(57) **CLAIM**

The ornamental design for a disposable laser tip, as shown and described.

DESCRIPTION

FIG. 1 is an isometric view of a disposable laser tip showing our new design;

FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a rear view thereof.

The dash-dot lines immediately adjacent the shaded areas represent the bounds of the claimed design. The even dash line shown in FIG. 7 is included for the purpose of illustrating environment and forms no part of the claimed design.
